Primary Examiner — Darlington Ly

(74) *Attorney, Agent, or Firm* — Morgan, Lewis & Bockius LLP

(57)

CLAIM

The ornamental design for an electric vehicle charging device as shown and described.

DESCRIPTION

FIG. 1 is an upper left front perspective view of an electric vehicle charging device showing our new design; FIG. 2 is an upper right rear perspective view thereof; FIG. 3 is a front elevational view thereof; FIG. 4 is a right-side elevational view thereof; FIG. 5 is a rear elevational view thereof; FIG. 6 is a left-side elevational view thereof; FIG. 7 is a top plan view thereof; FIG. 8 is a bottom plan view thereof; FIG. 9 top left front perspective cutaway view thereof; FIG. 10 is a left-side and enlarged elevational cutaway view thereof; and, FIG. 11 is an enlarged bottom plan view thereof.

(Continued)

The broken lines depict portions of the electric vehicle charging device that form no part of the claimed design

1 Claim, 5 Drawing Sheets

Related U.S. Application Data

continuation of application No. 29/771,060, filed on Feb. 19, 2021, now Pat. No. Re. 48,837, which is a division of application No. 29/707,818, filed on Oct. 1, 2019, now Pat. No. Re. 48,500, which is an application for the reissue of Pat. No. Des. 844,559.
